UNITED STATES PATENT OFFICE.

JOHN E. BOOTH, OF BANGOR, MAINE.

DESIGN FOR THE ORNAMENTATION OF MOCCASINS OR SHOES.

SPECIFICATION forming part of Design No. 18,186, dated March 20, 1888.

Application filed October 27, 1887. Serial No. 253,563. Term of patent 7 years.

To all whom it may concern:

Be it known that I, JOHN E. BOOTH, a citizen of the United States, residing at Bangor, in the county of Penobscot and State of Maine, 5 have invented a new and Ornamental Design for Shoes or Moccasins, of which the following is a specification.

My invention relates to a design for the ornamentation of shoe or moccasin tips, and it 10 is hereinafter fully explained in connection with the accompanying drawing, wherein the figure is a view of a shoe or moccasin the tip of which is ornamented with the design in accordance with my invention.

15 A represents the tip of the moccasin or shoe, of any ordinary or preferred shape, in which is worked the design.

20 B B represent short parallel lines, and C C represent similar parallel lines which intersect the lines B at an angle, and thus form small checks or squares D D. A series, E, of

intersecting lines, arranged as shown, is disposed near each side edge of the tip A, and a similar series is disposed midway between the side series.

25 Having thus described my invention, I claim—

The design for the ornamentation of shoe or moccasin tips, consisting of a series of short parallel lines, B B, a series of short parallel 30 lines, C C, inclined to the lines B B and intersecting the same, and the small squares or checks D D, inclosed between the said intersecting lines, substantially as set forth.

In testimony that I claim the foregoing as my 35 own I have hereto affixed my signature in presence of two witnesses.

JOHN E. BOOTH.
